WALKING DOLL

Herbert E. Price, Auckland, New Zealand

Application April 24, 1956, Serial No. 580,262

4 Claims. (Cl. 46—105)

This invention relates to a walking or animated doll. An object of this invention is to provide in a doll construction, an improved mechanism for effecting walking of the doll and motion to the arms thereof.

Another object of this invention is to provide in a walking doll a spring motor with cam operated levers in each leg for effecting movement of each leg and also movement of each arm.

A further object of this invention is to provide an improved leg mechanism which includes the alternate projection and retraction of a roller in each leg, and the alternate projection and retraction of a pusher foot in each leg.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawings:

Figure 1 is a detail front elevation of a figure toy constructed according to an embodiment of this invention.

Fig. 2 is a detail side elevation of the device.

Fig. 3 is a skeleton view showing the operating mechanism within the body and legs of the toy.

Fig. 4 is a detail side elevation of the operating mechanism.

Fig. 5 is a sectional view taken substantially on the line 5—5 of Fig. 3.

Fig. 6 is a sectional view taken substantially on the line 6—6 of Fig. 3.

Fig. 7 is a sectional view taken on line 7—7 of Fig. 3.

Fig. 8 is a detail side elevation of one of the operating levers.

Fig. 9 is a detail side elevation of another one of the operating levers.

Fig. 10 is a perspective view of the connecting link between the operating levers and the foot lever.

Fig. 11 is a bottom plan view of one of the feet.

Referring to the drawings, the numeral 15 designates generally a frame structure embodying outer plates 16 and 17 and an intermediate plate 18. The plates 16, 17 and 18 are connected together by means of bolts 19 and 20 and an intermediate bolt 21 is secured between plate 17 and intermediate plate 18. The bolts 19 and 20 also provide means for supporting and spacing the intermediate plate 18 with respect to the outer plates 16 and 17. A spring motor generally indicated at 22, is disposed within the frame 15 and includes a spring 23 with a spring operated drive shaft 24. The drive shaft 24 has one gear 25 of a gear train generally indicated at 26, fixed thereto. The gear train extends to the outer end of the frame 15 and includes a double blade governor 27 mounted on the gear shaft 28. An obtusely angled stop lever 29 is mounted on a pivot member 30 secured

to outer plate 17 and the stop lever 29 includes an outwardly projecting bell crank lever 31 by means of which the obtusely angled arm of lever 29 may be swung upwardly to governor engaging position or may be swung outwardly and downwardly to governor releasing position. A lower gear 32 mounted on a shaft 33 meshes with driving gear 25. The shaft 33 extends between plates 16 and 17 and loosely engages through intermediate plate 18. Shaft 33 has fixed at each end thereon a pair of oppositely disposed circular cam members 34 and 35. Cam member 34 is an inner cam member and rotatably engages within a ring 36 formed at an intermediate point in an elongated lever 37. The lever 37 is provided with a longitudinally elongated slot 38 through which a headed bolt 39 loosely engages. The bolt 39 is secured in the lower portion of plate 17. The lever 37 is formed with an offset lower end 40 and the upper end of the lever 37 includes an obtusely angled arm or lever 41. The lever 41 constitutes an arm operating lever and the upper end of lever 41 is connected by means of a sliding bolt 42 to a crank arm 43. The arm 43 is pivotally secured as at 44 to the upper end portion of the plate 17. Crank arm 43 is provided with a longitudinally elongated slot 45 within which the pin or bolt 42 slidably engages. Cam member 35 engages within a cam ring 46 disposed at the upper end of an elongated foot operating lever 47. The lever 47 is provided with an offset lower portion 48 on the lower end of which a roller 49 is rotatably mounted. Lever 47 is provided with a longitudinally elongated slot 50 through which a pivot bolt 51 loosely engages. The bolt 51 extends through an arm 52 forming part of a U-shaped member generally indicated at 53, which is carried by a flat bar or link 54. The upper end of the bar or link 54 is secured by means of a screw 55 to the lever 37. The bar or link 54 includes an offset lower portion 56 having an elongated slot 57 through which a screw 58 loosely engages, the screw 58 being secured in the upper end of a foot supporting lever 59. The foot supporting lever generally indicated at 59 is pivotally secured as by a bolt 60 to the lower end portion of lever 37, the bolt 60 loosely engaging through an opening 61 formed in the lower portion of lever 37. Bolt 60 also passes through an elongated lower slot or opening 62 which is formed in the lower portion 48 of lever 47. Foot operating lever 59 is provided with a right-angularly disposed lower end 63 through which a screw 64 is threaded and the screw 64 provides a means for attaching an apertured base plate 65 to the lower end or flange 63. The plate 65 forms the sole or bottom of a shoe generally indicated at 66. The foot supporting lever 59 is adapted to be rocked by rocking movement of link 54 by the slidable motion of the bolt 58 in the slot 57, the bolt 58 being secured to the upper portion of lever 59. The shoe 66 has a hollow leg 67 secured thereon, and the leg 67 encompasses the levers 37, 47, 59 and 54. A hollow torso element 68 loosely encompasses the motor frame 15 and the torso member 68 includes a neck portion 69 on which a head 70 is mounted. The pivot 44 of the crank arm 43 has mounted thereon a rubber or resilient stud 71 about which a socket 72 engages. The socket 72 is formed at the upper or inner end 73 of an arm 74. Each foot 66 has formed in the bottom plate 65 thereof an elongated slot 75 through which the roller 49 is adapted to be extended. The spring 23 is wound by means of a tubular projection 76 which extends laterally through the torso 68 at a point below one of the arms 74.

In the use and operation of this toy the spring motor 22 is wound up by winding the shaft 76. At this time the locking lever 29 is in the locked position shown in Fig. 5. Downward rocking of lever 31 which extends outwardly through the rear of the torso 68 as shown

in Fig. 2, will release governor 27. At this time the gear train is set in motion and the leg operating shaft 33 will rotate the cams 34 and 35 so as to effect forward and rearward swinging with up and down motion with the levers 37 and 47. As lever 47 is raised roller 49 is moved upwardly above the bottom of plate 65, and the opposite pair of cams 34 and 35 which operate alternately or in opposite directions to the first pair of cams will effect downward movement of lever 47. As lever 47 on one side is lowered the rocking of the pairs of levers 37 and 47 will effect animation to the legs so that one leg will move forward and the roller 49 is projected below a foot, and the other leg will remain stationary at the bottom in view of the contact of the sole plate 65 with the supporting surface. The construction of the toy hereinbefore described is such as to provide animation or motion to both the legs and the arms, and this animation is effected without having the toy tip over.

What is claimed is:

1. In a walking doll toy of the class described, the combination of a torso, a pair of side plates in said torso, means securing said side plates together, a spring motor secured between said side plates, a drive shaft extending from said motor and rotatable by said motor, a gear train operable by said drive shaft, a leg operating shaft extending between and through said side plates and operable by said gear train, a pair of cam members mounted on each end of said leg operating shaft exteriorly of its adjacent side plate the cams of each pair being offset relative to the corresponding cam of the opposite pair, a pair of elongated leg levers and a pair of foot operating levers, each lever having a ring therein, the ring of each lever engaging one of said cams for oscillating movement relative to said leg operating shaft, a pair of flat bars pivotally secured to each elongated leg levers, a pair of foot supporting levers, a pin and slot connection between each flat bar and its associated foot

supporting lever, a second pin and slot connection between each elongated leg lever and its associated foot operating lever, a roller pivotally mounted to the lower extremity of each foot operating lever, a right angled portion at the extremity of each foot supporting lever, shoe portions each including a base plate having a slot therein, said rollers projecting through said slots, the eccentric motion of said rings of said elongated leg levers and said foot operating levers about said cams causing progressive extension of one of said rollers as each leg is successively advanced while the other of said rollers is retracted so that the opposite leg lever and foot operating lever remain stationary.

2. The structure of claim 1 wherein said torso is provided with oppositely disposed arm portions mounted for oscillating movement adjacent the shoulders, a crank arm secured to the pivot point of each of said arm portions, an obtusely angled extension on each leg lever, a pin and slot connection between each extension and its associated crank arm, the arrangement being such that each arm swings rearwardly as the opposite leg swings forwardly.

3. The structure of claim 1 including a governor actuatable by said gear train, and a bell crank lever having one end extending exteriorly of said torso and its other end engageable with said governor to selectively actuate and de-actuate the mechanism.

4. The structure of claim 2 including a governor actuatable by said gear train, and a bell crank lever having one end extending exteriorly of said torso and its other end engageable with said governor to selectively actuate and de-actuate the mechanism.
